UNITED STATES PATENT OFFICE.

WILLARD G. STAPLES, OF NEWBURYPORT, MASSACHUSETTS, ASSIGNEE, BY MESNE ASSIGNMENTS, TO FEDERAL METALLIC PACKING COMPANY, OF BOSTON, MASSACHUSETTS, A CORPORATION OF MASSACHUSETTS.

TWISTING-MACHINE.

1,106,899.

Specification of Letters Patent. Patented Aug. 11, 1914.

Application filed March 15, 1909. Serial No. 483,398.

To all whom it may concern:

Be it known that I, WILLARD G. STAPLES, a citizen of the United States, residing at Newburyport, in the county of Essex and 5 State of Massachusetts, have invented a new and useful Improvement in Twisting-Machines, of which the following is a specification, reference being had therein to the accompanying drawings.

10 This invention relates to twisting machines for making string or cordage or for covering the same with a metallic envelop.

The objects of the invention are, first, to afford facilities for operating the machine 15 at a very high rate of speed and thereby make it highly productive; second, to provide for the reeling of the product as fast as it is finished and independently of the speed of the machine and, third, to permit 20 the reel when full to be quickly and easily removed and an empty reel installed.

The following is a description of the invention, reference being made to the accompanying drawings, in which,

25 Figure 1 is a view in perspective of the entire machine; Fig. 2 is a plan view of the same; Fig. 3 is a central vertical sectional view of the working parts of the machine the supporting standard and hangers being 30 shown in elevation; and Fig. 4 is a plan view of the spring which turns the reel.

In the drawings, 1 designates a standard of any suitable construction, having a head-portion 2 on which is mounted, in suitable 35 bearings, a shaft 4, held by a top-plate 5 secured to the head-portion 2 by bolts 6. An oil-cup 7 in the top-plate 5 provides for the lubricating of the shaft 4 which is bored longitudinally, the boring 8 being of a size 40 sufficient to receive the cord or string 9 made or covered by the machine. At one end the shaft 4 is provided with a driving-pulley 10, driven by a belt 11, and upon the other end is mounted a frame 12 which is 45 secured on the shaft between a collar 13 and a nut 14 and rotates with the shaft. The other end of the frame 12 is provided with a spindle 15 which is journaled in suitable bearings 16 on hangers 17 attached to the 50 floor. By supporting the frame 12 at both ends by means of the legs 17 and the shaft 4, it may be rotated at practically an unlimited rate of speed without vibration or danger to the machine. Between the head 2 and

the frame 12 the shaft 4 passes through a 55 bracket 18 spring from the head 2 and upon this bracket and also pierced by the shaft 4 is fixedly mounted a gear 19 which coöperates with other parts to turn a reel as will herein-after be explained.

Within the frame 12 is rotatably and 60 removably mounted a reel 20 upon which is wound the finished string or cord 9 as it is twisted by the rotation of the shaft 4 and frame 12. The reel 20 when full is removed 65 from the machine and an empty reel mounted therein and in order that this change may be accomplished as expeditiously as possible the following means are provided. The reel 20 turns on two spindles 21 and 22 set 70 in opposite sides of the frame 12, the spindle 22 being movable longitudinally within a sleeve 23 secured in the frame 12. The spindle 22 has near its lower end an enlarged portion 24 which serves a double purpose. 75 The interior of the sleeve 23 is of sufficient diameter to receive the enlarged portion 24 of the spindle 22 and a coil spring 25 encircles the spindle 22 within the sleeve 23 and bears against the inner face of the enlarged portion 24 the other end of the spring bearing against a knurled nut 26 screw-threaded within the sleeve 23. In its upper end the spindle has an aperture 27 for the insertion of a tool to force the spindle out- 80 wardly against the spring 25 to release the reel. The reel may be released by unscrewing the knurled nut 26 instead of using a tool in the aperture but the former method is more expeditious. The outer face of the 85 enlarged portion 24 bears against one side of the reel 20 to prevent the spindle entering the hub of the reel too far and also to force the reel against a friction spring 28 secured to a beveled gear 29 which turns on 90 the fixed spindle 21. The friction spring 28 has a plurality of arms, each carrying a leather shoe 30 which contacts the side of the reel 20 and tends to carry the reel around when the gear 29, to which the spring is at- 95 tached, rotates. Gear 29 is held in place on the spindle 21 by set-nuts 31, and is turned by a beveled-pinion 32 mounted on one end of a small shaft 33 supported in a bearing 34. The other end of the shaft 33 passes 100 through the end of the frame 12 nearest the head 2 and carries a gear 35 which meshes with the fixed gear 19. In order to counter-

balance the weight of these gears and shaft a counter weight 36 is secured on the other side of the frame 12.

The machine, which is not automatic in that it requires the constant attendance of an operator to hold together the materials to be twisted into string form and to control the reeling of the finished product, operates as follows: The ends of the materials are passed through the boring 8 in the shaft 4 and then fastened to the reel 20. The operator stands on the opposite side of the machine near the driving pulley 10, holding the materials together as shown in Fig. 1 and permitting the materials to be drawn through his hands as fast as required. When the machine is operated, the shaft 4 and frame 12 are rotated at a high rate of speed which of course twists together the materials between the reel and the hands of the operator. As the twisting process continues the operator permits the finished product to be drawn into the machine by the reel 20 and wound up thereon. As the frame 12 rotates, the gear 35, meshing with the fixed gear 19, travels around the latter and is thereby rotated, turning the gear 29 through the medium of the rod 33 and beveled pinion 32. The leather shoes 30 on the friction-spring 28 bear against the reel 20 and tend to turn it with the gear 29. The twisting of the reel 20 is, however, under the direct control of the operator and unless he releases the material or string 9 the reel cannot be turned and the shoes 30 slide on the side of the reel. The moment the operator releases the string 9 the shoes on the friction-spring catch the side of the reel and turn it until the slack in the string 9 is wound on the reel. When the reel 20 is filled, the machine is stopped momentarily, the string 9 is cut near the reel, the spindle 22 is raised against the pressure of the spring 25 by means of a tool inserted in the aperture 27 or is released by unscrewing the knurled nut 26 and the reel is removed from the machine. An empty reel is at once installed by placing it on spindle 21 permitting spindle 22 to be forced into the other end of the hub of the reel by the spring 25 and then securing the string 9 to the reel. It is obvious that the operation of changing the reel on the machine may be accomplished with great facility and in a moment, thus hardly interfering with the continuous operation of the machine.

It is to be observed, and this is an important feature of the machine, that the frame which carries the reeling mechanism is supported at both ends and is evenly balanced.

This construction presents several advantages. In the first place it greatly increases the production of the machine since the production depends entirely upon the speed of the machine and this construction permits running the machine at a very high rate of speed without danger. Secondly, there is little or no vibration and the wear and tear on the machine due to that cause is practically eradicated. Thirdly, it permits the various parts to be made much lighter and yet just as serviceable.

Another important feature resides in the means employed for reeling up the finished product as fast as it is produced and under the complete control of the operator. Great difficulty has heretofore been experienced in the use of gears for this purpose owing to the fact that as the reel fills up each revolution of it winds up a longer portion of the product. By the use of the friction-spring, however, the speed of the reel can be controlled exactly by the operator.

What I claim is:

1. A twisting machine, having, in combination, a frame rotatably mounted, two spindles mounted on opposite sides of said frame, one of which is fixed and the other longitudinally movable, a reel rotatably mounted between said spindles and adapted to turn thereon, a gear mounted on said fixed spindle, a friction spring secured to said gear and contacting one side of said reel, means to turn said gear and said spring when said frame is rotated and adjustable means for forcing said reel against said friction spring.

2. A twisting machine comprising a rotatable frame, a spindle fixed on one side of said frame, a friction spring mounted on said spindle, means for turning said friction spring when said frame is rotated, a sleeve fixed in the opposite side of said frame, a spindle having an enlarged portion mounted within said sleeve and longitudinally movable therein, a nut threaded into the outer end of said sleeve, a helical spring in mounted on said last mentioned spindle and abutting at one end said enlarged portion of said spindle and at the other end said nut, for forcing said spindle inwardly and a reel mounted on and between said fixed spindle and said movable spindle.

In testimony whereof, I hereunto set my hand, in the presence of two subscribing witnesses, this the ninth day of March, 1909.

WILLARD G. STAPLES.
